IGNITION DEVICE

Cecil R. Benton, Vergennes, Vt.

Application October 28, 1937, Serial No. 171,457

5 Claims. (Cl. 123—169)

This invention relates to igniters and more particularly to spark plugs especially adapted to withstand severe operating conditions.

Spark plugs for such uses must withstand high temperatures and pressures, and their insulation must be able to resist the high voltage necessary to produce a satisfactory spark under these conditions. In addition, the plugs must withstand severe vibration and large temperature changes which further increase the difficulty of providing plugs that will operate satisfactorily for a reasonable length of time.

Plugs for such purposes have been developed in which mica is used as the insulating medium. Many of such plugs wrap the central spark plug electrode in a mica sheet, this forming the electrical insulation. Surrounding the spirally wrapped mica may be placed layers of mica resembling a stack of washers, these forming a mechanical protection for the electrical insulating tube formed by the spiral layers of the mica sheet.

It has heretofore been difficult for the manufacturer to wrap the mica sufficiently tightly to form a gas-tight seal. Another difficulty is the avoidance of air spaces between the mica washers and the mica tube. These spaces are objectionable because they become filled with ionized gases which form a path for leakage electric current. Many attempts to compress the mica tube have resulted in rupturing the sheet from which it is formed. To prevent gas pockets attempts have been made to fill them beforehand with materials which will not ionize.

Both these objections are not completely solved by the remedies which have heretofore been tried and it is therefore one of the principal objects of this invention to provide a spark plug which will not be subject to the above mentioned causes of deterioration. More specifically, it is an object of the present invention to provide a spark plug in which the mica tube surrounding the central electrode is tightly compressed over a substantial portion of its length and in which the mica washers have a tight fit on the mica tube which passes through them.

Another object of this invention is to provide a method of assembling a spark plug so that the layers of the mica tube are placed under extreme radial pressure without subjecting them to so great a circumferential tension as to induce the formation of cracks or fissures.

Other objects of this invention will more fully appear from the following detailed description taken in connection with the accompanying drawing which illustrates the preferred embodiment thereof and in which:

Fig. 1 is a longitudinal sectional view of a spark plug incorporating my invention.

Fig. 2 is a cross-section taken on the line

2—2 of Fig. 1 and looking in the direction of the arrows.

Fig. 3 is a cross-section taken on the line 3—3 of Fig. 1 and looking in the direction of the arrows.

Fig. 4 is an end view looking up at the bottom of the spark plug.

The particular embodiment of the invention shown in the drawing comprises a shell 10 externally threaded at its lower end 11, as is common practice, and having a collar 12 to receive a gasket and a hexagonal portion 13 to receive a wrench. A nut or bushing 14 having an integral tubular extension 15 is screwed into the top of bore 16 of the shell 10, the tubular extension serving as a radio shield. The nut 14 presses down on a collar 18 on a gland 20, forcing the tapered lower end of the gland down into the tapered lower position of the bore in the shell 10 and producing a gas-tight joint between the gland and the shell.

The gland 20 surrounds a central electrode 21, made of steel or other equivalent material, and the mica which forms its insulation. The stem of the electrode 21 is cylindrical and is surrounded by a tapered sleeve 22, the larger end of the sleeve being at the lower end of the electrode. The sleeve 22 is preferably made of a material softer than that forming the electrode 21 such as brass, and is surrounded by a spirally tapered tube of mica 23 formed of one or more sheets wrapped several times around the electrode. The electrode 21 and the sleeve 22 cooperate to form a conducting path.

The electrode 21, the brass sleeve 22, and the mica tube 23 fit tightly in a tapered hole extending through the bushing or gland 20 and also project some distance above and below. The portions of the tube projecting from the gland 20 are enclosed in two stacks of mica washers 24 and 25. The mica washers 24 around the upper part of the tube are clamped vertically between the top of the gland 20 and a metal washer 26, the upper end of the electrode 21 being flanged or spun over to hold the parts together. The mica washers 25 around the lower part of the tube are similarly clamped between the lower part of the gland 20 and a head 29 on the electrode, and, in addition, the upper part of this group of washers fits into a counterbore in the bottom of the gland 20 and are surrounded by a skirt 30 forming the wall of the counterbore.

The head 28 of the center electrode 21 is provided with a tip 32 brazed or welded on and made of an alloy which is especially resistant to the eroding effect of electric sparks. A second electrode 33, made of the same alloy, extends across and is brazed or welded to, the lower end of the shell 10 under the center electrode tip 32.

and at the proper distance from it to provide the best spark.

The spark plug is assembled by tightly winding several layers of thin sheet mica onto a tapered 5 arbor or mandrel to form the tube 23. The lower mica washers 25, the bores of which have been 10 tapered, are slid over the tube which is then pushed through the gland 20 and through the upper mica washers 24. As the mandrel and 15 tube are pushed home by hand, a movement of the different layers of the tube relative to each other occurs. This movement consists of a slight longitudinal sliding of each layer, and a simultaneous unwinding of the tube so that its 20 initial tight fit is maintained.

The friction between the mandrel and the inner layer of the tube, and that between the outer layer of the tube and the gland causes the 25 longitudinal sliding of the layers relative to each other, and, once the static friction has been overcome, then circumferential motion between the layers will take place and the layers of the tube thus adjust themselves to the space which they 30 are to occupy.

25 After the mandrel and the tube are pushed home in the gland 20, the mandrel is withdrawn and the brass sleeve 22 is pushed into its place, but, while the mandrel was pushed in by hand, the brass sleeve is forced in by a press. It has 30 been found that, in assembling a spark plug of conventional size, a pressure of a thousand pounds on the end of the sleeve produces excellent results. This great pressure forces the brass sleeve in further than the mandrel went and causes 35 more motion of the layers of mica. As a result of this final movement and the wedging action of the tapered sleeve, the mica is under great radial pressure without being under excessive circumferential tension, and the space between the 40 layers of the tube and between the tube and the mica washers 24 and 25 is thus made gas tight.

The electrode 21 is then forced into place, expanding the brass sleeve 22 slightly or, if the sleeve was compressed near its inner end by the 45 wedging action on its sides as it was forced in, re-expanding it to its original size. This expansion or re-expansion of the brass sleeve is slight, but it places the mica tube under such extreme pressure that it remains tight and proof 50 against infiltration of gas or other products of combustion even after the plug has repeatedly been heated up to extreme operating temperatures and cooled down again to atmospheric temperatures. The expansion of the brass sleeve 22 55 also forces the tube 23 to fit tightly inside of the mica washers 24 and 25 so that no space is left into which destructive gases or particles might find their way.

While I have herein described in some detail 60 a specific embodiment of my invention, which I deem to be new and advantageous and may specifically claim, I do not desire it to be understood that my invention is limited to the exact details of the construction, as it will be apparent 65 that changes may be made therein without departing from the spirit or scope of my invention.

I claim:

1. In a spark plug, an electrode and a sleeve 70 combining to form a conductor having a tapered exterior, a bushing, and layers of insulating material between said conductor and bushing some of said layers lying substantially parallel to the

axis of said conductor and some of said layers lying in spaced stacks substantially perpendicular to said conductor, the tapered portion of the conductor extending entirely through all of 5 said layers.

2. In a spark plug, a shell, a central electrode mounted therein and having a shoulder, and means for forming a gas-tight electrically insulated seal between said electrode and said shell, 10 said means including a tube formed of layers of insulating material wrapped cylindrically about said electrode, a stack of washers of insulating material surrounding said tube for only a portion of the length thereof, and a hollow sleeve between 15 said electrode and said tube, said sleeve bearing against said shoulder and having a tapered exterior extending throughout substantially the full interior length of said stack and tube, said sleeve being made of a material sufficiently ductile to conform to irregularities on the inner surface of said tube and expand said tube radially outwardly without deforming the individual layers forming said tube, thereby closing the gap 20 between said stack and said tube and also the gap between said tube and said shell. 25

3. In a spark plug, a shell, a central electrode mounted therein and having a shoulder, and means for forming a gas-tight electrically insulated seal between said electrode and said shell, 30 said means including a tube formed of layers of insulating material wrapped cylindrically about said electrode, a stack of washers of insulating material surrounding said tube for only a portion of the length thereof, and a tapered hollow sleeve between said electrode and said tube and 35 bearing against said shoulder, whereby when said shoulder is pressed axially of said tube, the tapered exterior of said sleeve will radially expand said tube and said shoulder will axially compress said stack against said shell. 40

4. In a spark plug, an outer body having an electrode affixed thereto, an inner electrode assembly removably mounted in said body, said assembly comprising a central electrode having a shoulder adjacent each end thereof, a supporting shell surrounding the mid-portion of 45 said electrode, a tube formed of layers of insulating material lying in contact with the inner surface of said shell, said tube extending substantially the full distance between said shoulders, a stack of annular layers of insulating material surrounding and in contact with said tube and extending between each end of the supporting shell and the shoulders on said central electrode, and a hollow sleeve surrounding 50 said central electrode and extending throughout substantially the full length of said tube, said sleeve having an exterior tapered surface throughout substantially its full length whereby to expand said tube into gas-tight contact with 55 said stacks and said shell. 60

5. In an igniter, an electrode having a stem, a sleeve on said stem formed of a metal softer than said stem and having an exteriorly tapered portion, insulating material including layers of 65 insulating material perpendicular to said stem and surrounding at least the lower portion of said tapered portion, and a retaining member surrounding said insulating material and extending above said perpendicularly arranged layers. 70

CECIL R. BENTON.
